Filed Aug. 20, 1973, Ser. No. 389,862

Term of patent 14 years

Int. Cl. D13—03

U.S. Cl. D26—13 R

FIG. 1 is a side elevational view of a reed for a reed switch assembly;

FIG. 2 is a right end view thereof;

FIG. 3 is a left end view thereof;

FIG. 4 is a bottom plan view thereof;

FIG. 5 is a top plan view thereof;

FIG. 6 is a side elevational view of a modified form of the reed described in FIG. 1 showing our new design;

FIG. 7 is a right end view thereof;

FIG. 8 is a left end view thereof;

FIG. 9 is a bottom plan view thereof;

FIG. 10 is a top plan view thereof;

FIG. 11 is a side elevational view of a modified form of the reed described in FIG. 1 showing our new design;

FIG. 12 is a right end view thereof;

FIG. 13 is a left end view thereof;

FIG. 14 is a bottom plan view thereof;

FIG. 15 is a top plan view thereof;

FIG. 16 is a side elevational view of a modified form of the reed described in FIG. 1 showing our new design;

FIG. 17 is a right end view thereof;

FIG. 18 is a left end view thereof;

FIG. 19 is a bottom plan view thereof;

FIG. 20 is a top plan view thereof;

FIG. 21 is a side elevational view of a modified form of the reed described in FIG. 1 showing our new design;

FIG. 22 is a right end view thereof;

FIG. 23 is a left end view thereof;

FIG. 24 is a bottom plan view thereof;

FIG. 25 is a top plan view thereof;

FIG. 26 is a side elevational view of a modified form of the reed described in FIG. 1 showing our new design;

FIG. 27 is a right end view thereof;

FIG. 28 is a left end view thereof;

FIG. 29 is a bottom plan view thereof; and

FIG. 30 is a top plan view thereof.

The ends are shown fragmentary on one end and broken away at the other end to show indeterminate length. The sides opposite to the sides shown in FIGS. 1, 6, 11, 16, 21 and 26 are mirror images of these figures respectively.

We claim:

The ornamental design for a reed for a reed switch assembly, as shown and described.
